BANDAGE

Charles S. Beardsley, Elkhart, Ind.

Application May 6, 1946, Serial No. 667,655

2 Claims. (Cl. 128—156)

1

This invention relates to new and useful improvements in bandages, and it has particular relation to a new and useful improvement in bandages of the ready-to-use type which are adapted to protect injuries to the thumb and fingers.

In recent years, bandages of the ready-to-use type, for application to the thumb and fingers, have become popular. These members receive most of the day-to-day minor traumatic injuries. One of the most common forms of such bandages is sold under the trade name Band-Aid. These ready-to-use bandages are packaged in individual containers in a sterilized condition.

To apply one of these bandages, it is merely necessary to remove the wrapping and place the bandage upon the injured finger or thumb. Usually the bandages take the form of a strip of adhesive tape carrying a multi-ply pad of gauze or similar fabric in the central portion thereof. In some cases, the pad is impregnated with an antiseptic material such as Mercurochrome or sulfa compound.

The strips of adhesive tape are of such lengths that they are in excess of the diameter of the average finger or thumb, so that where the ends come together, there is a bulky overlap.

This overlap is undesirable for several reasons. It constitutes a waste of material, and annoys the wearer. Furthermore, because of the overlap, the bandage tends to form a self-supporting section or cylinder, thereby separating from the finger to which applied. This is particularly true where the tape is rather heavy or stiff.

The present invention provides a bandage of the ready-to-use type which eliminates these undesirable features. Accordingly, the object of this invention may be stated as being the provision of novel and improved bandages of the ready-to-use type, wherein: there is no overlapping of the ends; there is no wastage of material; and, the bandage does not constitute a self-supporting section which tends to separate from the finger.

Other objects of the invention will, in part, be obvious and will in part appear hereinafter.

For a more complete understanding of the nature and scope of the invention, reference may now be had to the following detailed description thereof, taken in connection with the accompanying drawings, wherein:

Figure 1 is a plan view of a conventional ready-to-use type of bandage, illustrative of the prior art;

2

Figure 2 is an elevational view illustrating the application of the bandage of Figure 1 to a finger or thumb;

Figure 3 is a sectional view taken on line 3—3 of Figure 2;

Figure 4 is a plan view of an improved bandage of the ready-to-use type, provided in accordance with the teaching of the present invention;

Figure 5 is a view showing the application of the bandage of Figure 4 to a finger or thumb; and

Figure 6 is a sectional view taken on line 6—6 of Figure 5.

Referring to Figure 1 of the drawings, a conventional type of ready-to-use bandage for protection of injuries to the thumb and fingers, is indicated at 10. The bandage 10 is in the form of a rectangular strip of adhesive tape or equivalent material 11, having square ends 12. The strip 11 is provided with pressure sensitive adhesive material, as indicated.

A multi-ply pad 14 is carried midway between the ends 12. The pad 14 may be made up of plies of surgical gauze or like material. It may be impregnated with antiseptic agent.

Figures 2 and 3 show the manner in which the bandage 10 is applied to a finger or thumb. The bandage 10 is of such length that when applied to a finger, illustrated by the cylindrical section 15 in the drawings, there is an overlap of the ends 12, as shown in Figure 3. The result is a bulky and annoying irregularity in the otherwise smooth bandage.

This overlap not only constitutes a waste of material to the extent of as much as 20%, but is also objectionable in that by having the overlap, a self-supporting cylindrical section is formed which on flexure of the injured finger, tends to become separated therefrom.

In Figure 4 of the drawings, a bandage is indicated generally at 20, which forms one embodiment of my invention, and which eliminates the foregoing disadvantages of the conventional type ready-to-use bandage 10.

The bandage 20 comprises a strip 21 of adhesive tape, or equivalent material, and carries a multi-ply pad 22 intermediate the ends thereof. It will be noted that the strip 21, when laid out flat, takes the shape of a non-equilateral parallelogram. The ends 23 of the strip 21 are in the form of right triangles and carry a coating of pressure sensitive adhesive. The angles at the tips 25 should not be more than 45° in spread, and preferably should be around 40°.

The relationship of the areas of the triangular

ends 23, to the rectangular area covered by the pad 22, is important. Preferably, the combined areas of the triangular ends 23 should be greater than that of the rectangular area covered by the pad 22. The length of the longer parallel sides of the bandage 20 should be equal to the average finger circumference. In order to accommodate different sized fingers and thumbs, the bandage 20 may be made in different sizes as required.

In Figures 5 and 6 of the drawings, the manner in which the bandage 20 is applied to a finger, represented by the cylindrical section 26, is shown. It will be noted that the ends 23 do not overlap, but fit neatly onto the finger 26 with a narrow marginal space 27 therebetween. This space 27 may be somewhat wider or narrower than shown, depending upon the size of the finger 26.

There is no wastage of materials, due to overlapping of the ends. The bandage 20 does not form a self-supporting section tending to separate from the finger 26. And, the bandage 20 is neat and of uniform thickness.

What is claimed as new is:

1. A bandage of the ready-to-use type adapted to protect traumatic injuries to the thumb or

ends 23, to the rectangular area covered by the pad 22, is important. Preferably, the combined areas of the triangular ends 23 should be greater than that of the rectangular area covered by the pad 22. The length of the longer parallel sides of the bandage 20 should be equal to the average finger circumference. In order to accommodate different sized fingers and thumbs, the bandage 20 may be made in different sizes as required.

2. The bandage of claim 1 wherein the combined area of said right triangular strip ends is at least equal to the intermediate rectangular area of said strip.

CHARLES S. BEARDSLEY.
